UNITED STATES PATENT OFFICE.

JOHN I. WHITE, OF PIEDMONT, WEST VIRGINIA, ASSIGNOR OF ONE-HALF
TO J. S. HELFERSTAY, OF SAME PLACE.

TIRE-REPAIRING TOOL.

SPECIFICATION forming part of Letters Patent No. 681,089, dated August 20, 1901.

Application filed February 6, 1901. Serial No. 46,227. (No model.)

To all whom it may concern:

Be it known that I, JOHN I. WHITE, residing at Piedmont, in the county of Mineral and State of West Virginia, have invented a new and Improved Tire-Repairing Tool, of which the following is a specification.

This invention seeks to provide a simple and easily-manipulated tool for repairing bicyclettes, and particularly adapted for giving the puncture the necessary shape to properly receive the common type of "umbrella" plug in such manner that the said plug can be quickly applied to the punctured part of the tire to effectively close the same.

15 My invention comprehends, essentially, a combination - tool having adjustable parts whereby it can be arranged to first cut the puncture to a proper shape to receive the plug and then adjust in a manner to conveniently 20 force the plug through the prepared puncture.

My invention in its complete make-up embodies a spindle having an exteriorly-threaded body portion, a non-threaded portion that terminates in a reduced threaded end adapted 25 to receive the conical plunger-head having a smooth penetrating portion and having a base portion that terminates in a hollow cutting-tool, said tool also including a tubular plug-presser adapted to fit upon the reduced spindle end, an anvil being also provided which is slidably mounted upon the non-threaded end of the spindle to coat with the non-cutting plug and form an adjustable abutment against which the anvil is adapted to seat.

30 In its more subordinate features my invention consists in certain details of construction and peculiar combinations of parts, all of which will hereinafter be described, and particularly pointed out in the appended claims, reference being had to the accompanying drawings, in which—

Figure 1 is a view illustrating the manner in which the combined conical cutter-head and plunger is inserted through the rupture 45 in the tire. Fig. 2 is a vertical section of the tool and illustrates the manner in which it is manipulated to effect a cutting action. Fig. 3 is a view illustrating the manner in which the tool is used to push the rubber plug 50 through the prepared opening in the tire.

Fig. 4 is a perspective view of the several parts which constitute my improved tire-repairing tool. Fig. 5 is a perspective view of the repair-plug.

Referring to the drawings, in which like numerals indicate like parts in all the figures, 1 designates a T-shaped body, the shank 1^a of which has an enlarged exteriorly-threaded portion 1^b, that terminates at a shoulder 1^c, which forms the base or inner end of a smooth 60 spindle portion 1^d of a reduced diameter, the outer end of which is threaded, as at 1^e, the purpose of which will presently appear.

2 designates a winged nut, the hub portion of which has a flat outer bearing-surface 2^a, 65 which coacts with and forms an abutment for the inner end of the anvil 3, the body 3^a of which is made tubular and of a diameter sufficient to permit of said body portion 3^a moving freely over the large threaded portion of 70 the shank. The outer end of the anvil is made solid, as at 3^b, and the said solid portion on its inner face has a beveled seat 3^c to engage the shoulder 1^c of the shank, which shoulder 1^c limits the outward movement of 75 the anvil.

4 designates a combined plunger and cutter member having a conical shape whose outer surface is smooth and whose front edge terminates in a penetrating-point 4^a. The inner or base portion of the member 4 is made tubular, and its rear edge terminates in an annular cutting-rim 4^b, which has a diameter slightly less than that of the anvil 3, with which said rim coacts, as will presently be 80 explained. The plunger 4 also has a longitudinally-extending central threaded socket 4^c, whereby it can be detachably fitted upon the reduced threaded end 1^e of the spindle 1.

In the practical arrangement of my repair kit or tool different sizes of plungers 4 are used to provide for conveniently, quickly, and effectively cutting different-sized openings, in accordance with the character of the puncture, and to provide for the insertion of larger or smaller closing-plugs, as the character of the puncture may necessitate.

5 designates a tubular pusher internally threaded and adapted to fit upon the thread- 100

ed end 1^e of the reduced spindle portion 1^d of the member 1, and 6 designates an umbrella plug such as is commonly used for closing symmetrical-formed holes in the tire.

5 The manner in which my improved repairing-tool is used is explained as follows: The puncture is located and a conical plunger of a proper size is fitted upon the spindle of the main or body part of the tool, and the said 10 conical plunger is then pushed through the punctured part of the tire, the inner movement of the spindle end through the tire being limited by the anvil by reason of its greater diameter than the cutting-rim of the 15 plunger, and again by reason of the free movement of the anvil on the shank or spindle 1 the tool can be conveniently used for reaming or cutting out the ruptured part of tires of different thicknesses. The conical 20 plunger having been pushed through, the anvil is forced toward its cutting-rim by turning the winged nut 2, which causes the cutting-rim of the plunger to cut the circular or other symmetrical-shaped opening beginning 25 on the inner side of the tire, that part of the tire being removed, seating itself in the tubular socket of the conical cutter and plunger. The tire part thus cut out, together with the conical plunger, is then withdrawn 30 and the conical plunger removed and the pusher member 5 substituted therefor. The rubber plug 6 is then properly cemented and its bottom end inserted into the opening made in the tire, care being taken to retain hold of 35 the string 6^a, which is connected with the said plug 6, and the annular rim part of the said plug 6 is then forced through the tire-opening by pressing the pusher member 5 thereagainst. The entire rubber plug having been 40 pushed into the tire, pull on the string will draw the button part 6^b out through the said tire-opening, which it fits snugly and with the rim member 6^a held firmly seated against the inside of the tire in the usual manner. The

projecting button portion is then cut off flush 45 with the tread face of the tire.

I am aware that repair-tools including a plunger adapted to be inserted through the puncture and cutting members for making a symmetrical hole to receive the button-head 50 plugs have heretofore been provided. My invention differentiates, so far as I know, from such devices in the peculiar correlation of the conical plunger and cutter, the anvil, the winged nut, and the threaded shank or 55 spindle.

The pusher member 5 when not in use is held in a socket 5^x in the handle 1, as clearly shown in Figs. 1 and 2.

I therefore claim and desire to secure by 60 Letters Patent in the United States—

1. A repair-tool for the purpose specified, comprising a shank having a handhold, said handhold being formed with a socket, a nut threaded on the shank, an anvil slidable on 65 the shank, a plunger removably fitted to the shank, and a pusher member normally held in said socket, and adapted to be removably connected to the shank.

2. A repair-tool for the purpose described, 70 comprising a shank having a handhold provided with a socket, said shank having threaded portions of different diameters and an intermediate smooth surface, a plunger having a cutting edge, and internally threaded to fit the threads of the less diameter on the shank, an anvil slidable on the smooth surface, and having an internal diameter greater than that of the threaded portion of 75 larger diameter, and a pusher member detachably held in said socket, internally threaded to fit the lesser threaded portion of the shank.

JOHN I. WHITE.
